MECHANISM FOR DRAWING WIRE

Edwin J. McIlvried, Akron, Ohio, assignor to The
Vaughn Machinery Company, Cuyahoga Falls,
Ohio, a corporation of Ohio

Application August 8, 1936, Serial No. 94,999

4 Claims. (Cl. 205—16)

Within the past few years wire drawing processes and machines have been greatly improved so that much higher drawing speeds are now attainable than formerly. Most wire drawing machines after processing the wire through the various drawing dies coil the wire on a rotating drum commonly known as a block. The coil that forms on such block is somewhat loose, but at slow speeds remains reasonably compact and can easily be removed and tied up after the drawing operation is completed. However, at high speeds the centrifugal force acting on the component strands of the coil causes individual strands to fly outwardly and by thus extending unduly from the periphery of the block, they become entangled with other strands, so that the result is a tangled and unsightly coiled bundle. Such extended or projecting strands, furthermore, constitute a serious hazard from a safety standpoint.

One object of the present improved process and mechanism for drawing wire, accordingly, is to provide means whereby the drawing speed can be increased as desired and permitted by modern drawing practice, while at the same time overcoming or avoiding the detrimental conditions just referred to. To this end I provide a relatively stationary instead of a rotating drum or block, upon which the wire as drawn is laid and there accumulated into a coil or bundle. Another important feature of the invention is that it permits such accumulated coil of wire to be removed from the machine without stopping the latter or interfering with the continuity of the wire drawing process. This increases the capacity or output of the machine since there is no lost time occasioned by stopping it to remove coils of wire. Furthermore, the nature of the present improved process is such that breakage of the wire and other troubles, which at present cause frequent stoppage of the machine, are largely eliminated, while at the same time a much heavier bundle may be accumulated than in the present rotating block.

I am aware that it has heretofore been proposed to utilize a stationary block in a wire drawing machine, the wire after being drawn through the last drawing die entering a hollow spindle and passing out and around a flyer sheave, by means of which it is wound on such block. This method, however, of drawing and laying the wire on the block necessarily produces a twist in the wire after leaving the die. In other words, there will be one complete twist or turn torsionally of the wire for each turn around the stationary block and such twist

causes the resulting coil to be what is known as "wild," that is, the individual coils or strands are exceedingly springy and difficult to handle both in the bundle and in the further processing of the wire. By the present improvements, however, I avoid the difficulty just noted by locating the drawing die on the flyer and adjacent to the stationary block, so that while the nature of the process is such that a twist occurs in the wire for every turn of the block, such twist occurs before the final passage of the wire through the die and the resultant cold working of the metal by the latter removes the effect of the twist.

To the accomplishment of the foregoing and related ends, the invention, then, consists of the steps and means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings—

Fig. 1 is a side elevation of an individually motor driven self-contained unit designed for drawing wire in accordance with my present improved process; Fig. 2 is a central vertical section of such unit taken on the plane indicated by the line 2—2. Fig. 1; Fig. 3 is a broken transverse section of the same taken on the plane indicated by the lines 3—3 on Figs. 1 and 2; and Fig. 4 shows a modification in one of the detail features.

In the wire drawing unit illustrated in the several figures of the drawings, the shaft or spindle 1 which constitutes the central axis about which certain parts, as presently described, are caused to rotate, is shown as vertically arranged. It will be understood, however, that, if preferred, such shaft may just as well be disposed horizontally.

Said shaft 1 is suitably supported at its lower end in a step bearing 2 in the hollow frame structure 3 of the machine and is supported at an intermediate point by a bearing 4 in such frame, the upper end of the shaft projecting thereabove and having a pair of spaced bearings 5 and 6, whereby the drawing block 7 is journalled on such upper shaft end.

As shown, the block is of usual slightly tapering form and it includes an extension 8, in effect continuous therewith but of slightly reduced diameter at one or more points 9, 10. Such block, including the extension, is furthermore formed with a plurality of longitudinal stripping slots 11

extending downwardly from its upper edge to a point near its base, the upper portion 12 of such slots being preferably of V-shape, as shown in Fig. 1. In this figure it will be noted that only one slot 11 is illustrated and that its location is arbitrarily assumed.

Rotatably mounted in a bracket 15 fixed to and rising from one side of the main frame 3 of the machine is a transverse shaft 16 that at its inner end carries two symmetrically spaced sector shaped arms 17. The latter are so disposed as to be adapted, upon rotation of shaft 16, successively to engage a special locking slot or recess 14 formed in the block between two adjacent stripping slots 11, the effect of such engagement being to hold the block stationary, i. e., prevent rotation thereof on its support formed by bearings 5 and 6. Suitably journaled in the bracket 15 below the shaft 16 is a handled crank 18 connected with said shaft by reducing gearing 19 so that the sector on the inner end of the shaft may be swung or rotated in a vertical plane.

Keyed to the rotating spindle 1, immediately below the base of the block 1, is a circular plate or disk 20 formed with a depending flange 21 that is laterally enclosed by an upstanding flange 22 on the machine frame. The disk 20, which rotates conjointly with the spindle 1, carries a suitable die block 23 (see Fig. 3) mounted so as to lie tangentially with respect to the periphery of the block 1. Likewise carried by said disk adjacent the die is a sheave 24 disposed to rotate in the plane of the disk so as to pass to such die a wire received from a second sheave 25 which is rotatably attached to the spindle immediately below the disk about a horizontal axis.

Sheave 24, as shown in Figs. 2 and 3, is mounted in the supporting disk or flyer member so as to be angularly self-adjusting relatively to the plane of the latter. If desired, however, a corresponding sheave 24a, but mounted at a fixed angle to properly receive and guide the wire to the die, may be used, as shown in Fig. 4.

The spindle 1 is formed with a longitudinal bore 26 extending from its lower end to the periphery of the sheave 25 which, as clearly shown in Fig. 3, is partially inset in a suitable recess 27 formed in the spindle, and adjacent the lower end of said spindle is a third sheave 28 suitably journaled about a transverse axis in the base of the machine with its one side aligned with the bore 26 in the spindle. The sheave 28 is suitably enclosed and leading to the outer side thereof is a wire guide 29. The hollow rotating spindle, together with the disk 20 and the die 23 and sheave 24 carried thereby, also together with the sheave 25 directly supported on said spindle, is driven at any desired speed by suitable gearing 30 from a motor 31 or other source of power.

In operation the strand W of wire as it comes from a previous wire drawing stage or from a reel may, if desired, first be passed through a suitable tensioning and speed synchronizing device (not shown). Such strand then is entered through the guide 29 around the sheave 28 in the base of the machine. From the latter such wire passes upwardly through the hollow spindle 1 over sheaves 25 and 24 in the order named to the die 23 and finally onto the block 1. Such block being held stationary by engagement of one of the sectors 17 therewith and the end of the wire being suitably secured to such block, the effect of rotating the spindle so as to move the die 23 in a counter-clockwise direction, as viewed in Fig. 3, will be to draw the wire over the sheaves 75

through such die and lay it on the periphery of the block. The successive convolutions formed on the latter force the coil gradually upwardly from the base of the block onto the extension 8, and when a sufficient coil or bundle has accumulated, this may be removed in the following manner. The operator will lower a stripping spider into the slots 11 in the block so as to engage only that portion of the coil that has accumulated above the base, leaving a number of convolutions still wrapped around the latter. The stripping spider is then raised so as to lift the portion of the coil engaged thereby and simultaneously the operator will rotate the shaft 16 so as to disengage the upper of the two sectors from the slot, wherewith it normally engages, thus clearing the way for the removal of the coil that is being stripped. However, before such upper sector releases the block, the other sector 20 will engage the lower portion of the same slot. The manner in which the sectors thus operate will be readily understood upon referring to Fig. 1, where they are shown in their normal positions in full lines and the intermediate positions, such as occupied incidentally to removal of the coil, in dotted outline.

From the foregoing description of the construction and operation of my improved wire drawing mechanism, it will be obvious that the wire passes directly from the die onto the stationary block without any torsional twist whatever being imparted thereto. Such twisting as is occasioned by bringing the wire to the die through the hollow spindle and over the sheaves will, of course, be removed by the drawing operation. The only rotating parts to the machine are the spindle with the circular plate or disk that carries the die and the last guide sheave 24. The only limitations, 30 accordingly, on the speed are in effect those imposed by the tensile strength of the wire and the wearing resistance of the die. The successive convolutions of the coil are laid closely on the stationary block, and as they are forced upwardly onto the portion of the block which is of reduced diameter, such convolutions nest together without tendency to fly off and become entangled with each other. As a result, a compact, uniform bundle is obtained, even when built up to much greater weight than is possible with the usual 40 drawing method, and as previously noted, such bundle may be removed without interrupting operation of the machine.

Other modes of applying the principle of my invention may be employed instead of the one explained, change being made as regards the means and the steps herein disclosed, provided those stated by any of the following claims or their equivalents be employed.

I therefore particularly point out and distinctly claim as my invention:

1. In wire drawing mechanism, the combination of a normally stationary block, a carrier rotatable about the axis of said block, a die on said carrier adapted upon rotation of the latter to lay the drawn wire on said block, and guide means adapted to lead a wire coaxially of said carrier and thence to said die, said guide means including two sheaves mounted on said carrier, one having its axis substantially parallel to but spaced from and the other having its axis transverse of and closely adjacent to the axis of said block.

2. In wire drawing mechanism, the combination of a normally stationary block, a rotatable spindle coaxial with said block, and a die carried by said spindle disposed on a line substantially tan-

gential to the periphery of said block and adapted upon rotation of said carrier to lay the drawn wire on said block, said spindle being formed with a central bore leading from one end thereof to a point approximately in the plane of said die, two sheaves carried by said spindle, one having its axis substantially parallel to but spaced from and the other having its axis transverse of and closely adjacent to the axis of said spindle.

3. In wire drawing mechanism, the combination of a normally stationary block formed with a longitudinally extending groove, a member rotatable about an axis transverse to that of said block and having arms adapted successively to engage

such groove, a carrier rotatable about the axis of said block, and a die on said carrier adapted upon rotation of the latter to lay the drawn wire on said block.

4. In wire drawing mechanism, the combination of a normally stationary block formed with a longitudinally extending groove, a member rotatable about an axis transverse to that of said block and having arms in the form of spaced sectors adapted successively to engage such groove, a carrier rotatable about the axis of said block, and a die on said carrier adapted upon rotation of the latter to lay the drawn wire on said block.

EDWIN J. McILVRIED.
